Specification for Design.

Patented Nov. 30, 1920.

Application filed November 24, 1919. Serial No. 340,422. Term of patent 14 years.

To all whom it may concern:

Be it known that I, JOHN FERN, a citizen of the United States, and a resident of Cincinnati, in the county of Hamilton and State of Ohio, have invented a new, original, and ornamental Design for Phonograph-Cases, of which the following is a specification, reference being made to the accompanying drawing, forming part thereof.

The figure is a perspective view of a phonograph case, showing my new design.

I claim:

The ornamental design for a phonograph case, as shown.

JOHN FERN.
